UNITED STATES PATENT OFFICE.

EDGAR B. SYMONS, OF LOS ANGELES, CALIFORNIA, ASSIGNOR TO SYMONS BROTHERS COMPANY, OF MILWAUKEE, WISCONSIN, A CORPORATION OF SOUTH DAKOTA.

CRUSHING HEAD.

Application filed January 24, 1925, Serial No. 4,377, which is a continuation of applications Serial Nos. 662,636 and 662,638, filed September 14, 1923. Divided and this application filed April 4, 1925. Serial No. 20,601.

To all whom it may concern:

Be it known that I, EDGAR B. SYMONS, a citizen of the United States, residing at Los Angeles, in the county of Los Angeles and State of California, have invented a certain new and useful Improvement in Crushing Heads, of which the following is a specification.

My invention relates to improvements in gyratory cone crushers, and particularly to crushing heads or cones therefor, and to means for moving and supporting and lubricating them.

One object is the provision of a simple and efficient oiling system. Another object is the prevention of the entrance of dust, water, or other foreign material into the bearings, and the reduction to a minimum of the leakage of oil. Another object is the provision of new and improved means for supporting the crushing head. Other objects will appear from time to time in the course of the specification and claims.

The present application is a division of my application 4377, filed on January 24, 1925 as a continuation of my prior applications 662,636 and 662,638, filed September 14, 1923.

My invention is illustrated more or less diagrammatically in the accompanying drawings wherein—

Figure 1 is a plan view;

Figure 2 is a section on the line 2—2 of Figure 1;

Figure 3 is a detail part section similar to Figure 2; and

Figure 4 is a vertical section of a variant form of my device.

Figure 5 is a detail.

Like parts are illustrated by like characters throughout.

A is a bed, upon which rests a frame A¹ outwardly flanged at A² for stiffness, and provided at its top with a reinforcing flange A³. A⁴ A⁵ are radial arms extending inwardly from the flange A¹ to support a rigid bearing sleeve A⁶. One side of this bearing sleeve carries a gear case A⁶ from which projects laterally the horizontal sleeve A⁷ pro-

jecting from the frame. The sleeve A⁵ terminates in a gear case A¹⁰ which is formed by a flange A⁸ projecting outwardly from the body of the sleeve A⁵, and closed by the bearing cap A⁹, there being an oil tight packing A¹⁰ between this cap and the top of the sleeve A⁸. The sleeve A⁵ is provided with a tightly fitted lining A¹¹.

B is an eccentric sleeve mounted for rotation in the bearing and having an outer babbitt bearing A¹². It is flanged at B² and has an annular ball bearing B¹ resting on the flanged upper end of the lining A¹¹ to support the downward thrust caused by the weight of the eccentric and its associated parts. B³ is a ring gear bolted or riveted to the underside of the flange B² surrounding the upper end of the bearing A⁸ and located within the gear case A¹⁰. B⁴ is a bevel pinion in mesh with the gear B³, mounted on the drive shaft B⁵ which shaft rotates in a bearing B⁶ carried by the two part split adjustable bearing support B⁷, which support is outwardly tapered and feathered in the sleeve A⁷. The two parts of the bearing support are adapted to be forced inwardly to adjust the bearing by means of feed screws B⁸ in the cap B⁹ which cap is bolted in place to close the open end of the sleeve A⁷. B¹⁰ is a belt pulley, keyed to the shaft B⁵.

The bearing cap A⁹ has at its upper side a spherical bearing surface which supports a segmental ball member C¹ having a babbitt facing C² to engage the spherical bearing surface. C³ is the crushing head or cone mounted on and integral with the segmental ball above referred to. It has a skirt C⁴ extending downwardly below the ball bearing and is provided immediately below the bearing covered by the skirt with a flange C⁵, having a spherical surface concentric with the ball bearing engaging an oil packing ring C⁶ in a spherical surface on the cap A⁹ which surface is also concentric with the ball bearing. C⁷ is a shaft mounted in the cone, tapered and locked by the compression ring C⁸ and the nuts C⁹. This shaft extends down through the cap A⁹ making a close fit

with the babbitt surface C^{10} on the inside of the eccentric sleeve B , so that when the sleeve is rotated the shaft will be gyrated and cause the cone to gyrate on its spherical bearing.

D is an inclined mantle, of manganese steel or other suitable material, carried on the cone, and supported for example by the packing D^1 of zinc or other suitable material. D^2 is a conic plug adapted to engage the upper portion of the mantle D to hold it in place, the abutting surfaces being substantially perpendicular to the surface of the cone. The plug is held in position for example by the nut D^3 .

E is a conical spider having a cylindrical flange E^1 adapted to penetrate and be vertically adjustable in the frame A^1 . It is provided with reinforcing ribs E^2 and three laterally extending lugs E^3 . Adjusting bolts E^4 are screw threaded in bosses E^5 on the ring A^1 , and pass through the lugs E^3 . The lugs E^3 are counter sunk at E^6 and supporting nuts E^7 and locking nuts E^8 have conical surfaces to engage these countersinks so that when the nuts E^8 have been slackened off the nuts E^7 may be rotated to raise or lower the spider and adjust it toward and from the crushing head or cone. E^9 is a concave mantle carried by the spider E provided with a zinc or other suitable packing E^{10} . Lugs E^{11} projecting from the lower edge of the concave are engaged by holding bolts E^{12} which pass upwardly through the flange E^1 and are held in place to support the mantle by the nuts E^{14} . The spider is outwardly flared above the cone to provide a funnel or hopper to guide the material to be crushed into the crushing area.

F is a pump housing closing the lower end of the sleeve A^6 . F^1 is a gear pump carried thereby and mounted on a shaft F^2 . F^3 is a crank disk rigidly attached to the gear pump and having an aperture adapted to be engaged by a crank pin F^4 which is thrust downwardly toward the disk by means of a spring F^{15} . In arranging this part of the apparatus the plug F^{16} is screw threaded into a hole in the end of the eccentric and a collar on the crank pin F^4 rests against this plug to prevent the spring F^{15} from throwing the plug out too far. The relative position of plug and collar is such that the crank pin can go down far enough to engage the hole in the crank disk. Taking the position shown in Figure 2, when the crank disk is put in place, the crank pin rides on the disk compressing the spring. As soon as the apparatus starts up the eccentric rotates until the crank pin is in line with the hole in the disk, when the spring forces the pin into the hole and from then on the crank pin is in the hole in the crank disk. F^5

is an oil pipe extending from a point above the bottom of the chamber F^6 through the conduit F^7 to the pump. Oil is discharged thus through the conduit F^8 and the pipe F^9 , conduit F^{10} to the annular conduit F^{11} by which the ball and socket bearing is lubricated. Oil passes out into the annular chamber F^{12} from the ball and socket bearing whence it drains into the conduit F^{13} into the gear chamber, and thus back to the oil well. Some of this oil will be passed through the conduit F^{14} to lubricate the bearing B^6 . F^{20} is an oil duct extending, as shown in Figure 2, from the oil conduit F^6 to the chamber beneath the eccentric and the main crusher shaft in which is located the crank disk F^3 . Oil passes through this duct F^{20} to fill this chamber and in response to the action of the pump F^1 . Since the cross sectional area of the passage F^{20} is very materially smaller than the cross sectional area of the conduit F^6 , this receives a relatively small proportion of the delivery of the pump, but sufficient to maintain the feed chamber full of oil and to force oil upwardly between the main crusher shaft and the eccentric B and between the eccentric B and the sleeve or bearing A^{11} . The oil which thus passes upwardly about the crusher shaft and eccentric finds its way either over the top of the eccentric or out through the ball bearings B^1 and finally flows back to the oil chamber F^6 . There is thus a complete circulation of oil through all of the bearings and the oil chamber being completely closed and there being no rotating packing employed lubrication troubles will be reduced to a minimum.

While the flange E^1 carries the spider E it makes a close fit in the frame A^3 and is more or less held against rotation by the adjusting screws E^4 . Still the crushing action is likely to cause creeping with respect to the frame as the radius along which the crushing pressure is applied sweeps round and round during the gyration of the cone. In order to prevent this creeping and resultant locking, jamming or breaking of the adjusting screws the upper portion of the frame is split at G and provided with horizontally disposed lugs G^1, G^2 . G^3 is a locking bolt passing through these lugs and associated with the lock nut G^4 , by which, once the concave has been properly adjusted for height, the frame may be clamped snugly on the spider to hold the parts against the creeping or displacement. The key I is also inserted in key ways cut in the frame and spider to assist in holding against creeping.

H is a bearing bed carrying a bracket H^1 and bearing H^2 . H^3 is a stop collar on the shaft B^5 to hold the shaft against lateral displacement so as to maintain the

pinion B⁴ with respect to the gear B³ in proper meshing relation.

The eccentric B carries, secured to its upper flange B² a removable counterweight 5 L, which in Figure 3 is shown as bolted to the gear B³ and adapted to rotate within the gear housing A¹⁶.

Referring to the variant form shown in Figure 4, N is a bearing cap having an upwardly concave spherical supporting surface N¹, to provide for the opposed spherical bearing surface N² of the head N³. The head is centrally apertured, and seats upon the upwardly tapered surface N⁶ of the 15 gyratory shaft N⁵, the lower section N⁷ of which penetrates within the eccentric aperture of the sleeve N⁸. The head is provided with a skirt N¹⁰ bolted or otherwise removably secured to a ledge N¹¹ about the head, 20 and terminating in a spherical surfaced flange N¹² adapted to engage the oil packing ring N¹³ in the spherical bearing surface N¹⁴ which is concentric with the main spherical bearing or supporting surface. 25 The upper end of the head is surrounded by a ledge O which is arcuate in cross section as at O¹, the arcuate portion forming a support for the hollow crushing cone O² which is inwardly flanged at the top as at 30 O³ about its central aperture to conform generally to the shape of the ledge.

Mounted upon the hollow cone is a mantle comprising the concentric rings P P¹ which may be of manganese steel or other 35 suitable material. P² is a securing or pressure transmitting ring adapted to engage the uppermost of the manganese mantle rings. The mantle rings may rest directly upon the hollow cone, but are preferably supported upon a layer of zinc or other suitable material P³.

S is a circumferential oil passage formed in the surface of the bearing surface N, and adapted to be supplied with oil, for example by the oil duct S¹, from any suitable oil source. S² is a circumferential oil well positioned between the main spherical supporting surface N and the supplemental bearing surface N¹⁴ in contact with the 45 flange N¹². The size of the well in relation to the movement of the cone is such that under normal circumstances the inner edge of the flange will not contact the inner wall of the oil well. S⁴ is a run-off oil passage 50 adapted to return the oil from the oil well to the main lubricating system of the crusher.

Although I have illustrated and described a practical and operative crusher, it will be 55 realized that I may make many changes in size, number, shape, disposition and location of parts without departing from the spirit of my invention, and that I wish my disclosure to be taken as in a broad sense 60 illustrative rather than as limiting me to

the specific device herein described and shown.

The operation of my invention is as follows—

When the machine is set up as shown in 70 the drawings and the drive shaft is rotated, it rotates the eccentric sleeve and thereby the causes the eccentric shaft to gyrate or wobble. The eccentric shaft in turn gy- 75 rates the conic crushing head which rocks or gyrates on its large spherical bearing. The head, in response to the movement of the eccentric sleeve and the eccentric shaft, gyrates about a point adjacent the apex of the cone, this central point being determined 80 by the curvature of the spherical bearing. As the head gyrates the point of closest approach between head and concave travels about the concave.

Obviously the crushing zone is filled with 85 dust and flying particles and it is a matter of extreme importance to provide a bearing which shall be substantially dust- proof and which, on the other hand, shall prevent the escape of the lubricant from the 90 preferably closed oiling system. In order to protect the main spherical bearing from the intrusion of foreign material I surround it with an open space or trap, represented herein by the circumferential oil 95 well or passage S. Outside of this passage I provide a second pair of opposed spherical bearing surfaces concentric with the main supporting bearing N. The engagement between the opposed surfaces may be 100 supplemented by a packing of any suitable type. In operation the packing is to some extent oil soaked, if only by the fact that the flange N¹² contacts the oil in the well, and wipes it across the packing. The de- 105 pending apron to a large extent protects this outer bearing from dust and flying particles.

In the form shown in Figure 2 the member C⁴ serves as such a protecting and dust-deflecting apron. In the form 110 shown in Figure 4 the corresponding service is performed by the hollow cone, which extends downwardly and outwardly beyond the flange. Assuming that some foreign material passes through the outer spherical 115 bearing it penetrates the interior only in the form of oil soaked particles, and it passes into the oil in the oil well. It drains thence by the passage to the main lubricating system and is filtered out or otherwise 120 disposed of in the course of the normal circulation of the oil. No foreign material can penetrate to the main spherical bearing 125 since there is a flow of oil outwardly across the bearing surface N². Of the oil pumped up through the duct S¹ some flows out across the periphery of the supporting bearing N¹, and some of it flows inwardly toward the central shaft of the crusher. The leakage of oil from the system is mini- 130

mized since the oil which flows into the peripheral oil well is drained thence by the passage S⁴.

I claim:

- 5 1. In a crushing machine, a gear case, having a circular top opening, a circular closure therefor having an upwardly extending bearing surface, lubricating passages contained within the wall of the housing 10 and the closure, pins unequally spaced interposed between the closure and housing, one of said pins being hollow and adapted to complete the connection between said oil passages.
- 15 2. A crushing head comprising a body having a spherical bearing surface intermediate its top and bottom, a skirt projecting downwardly below the bearing surface, and an annular lug projecting inwardly 20 from the skirt beneath and having a spherical surface concentric with the bearing surface.
- 25 3. A crushing head comprising a cone, the bottom of which has a downwardly disposed spherical surface, an apron depending downwardly from the cone, below the bearing surface, a lug extending inwardly therefrom and having a spherical surface concentric with the first mentioned bearing surface.
- 30 4. In a gyratory crusher, a bearing element provided with an upwardly concave spherical bearing, a crushing head adapted to be received by said concave spherical bearing and provided with a bearing surface 35 shaped to conform thereto, and means depending from said crusher head positioned beyond the normal limit of the engagement of the crusher head with the concave bearing, adapted to prevent the passage of foreign material to or from said bearing.
- 40 5. In a gyratory crusher, a bearing element provided with an upwardly concave spherical bearing, a crushing head adapted to be received by said concave spherical bearing and provided with a bearing surface 45 shaped to conform thereto, a protecting apron, depending from the cone, provided with a spherical bearing surface concentric with said concave bearing, a bearing element 50 opposed thereto, and a circumferential depression surrounding said concave spherical bearing, the bottom of said depression extending lower than the lowest point of contact of said apron and bearing element.
- 55 6. In a gyratory crusher, a bearing plate having an upwardly concave spherical bearing, a concentric supplemental bearing member surrounding it and spaced therefrom, having a spherical surface concentric with 60 the main bearing surface.
- 65 7. In a gyratory crusher, a bearing plate having an upwardly concave spherical bearing, a concentric supplemental bearing member surrounding it and spaced therefrom, having a spherical surface concentric with 70 the main bearing surface, and positioned at a greater distance than the main bearing from their common center.
- 75 8. In a gyratory crusher, a bearing member having an upwardly concave spherical bearing surface, an annular member surrounding such bearing surface, and having a concave spherical surface concentric therewith, an annular channel between said concave surfaces, the bottom of which extends 80 below the lowest point of both, and a crushing head having downwardly convex bearing surfaces engaging each of said concave bearing surfaces.
- 85 9. In a gyratory crusher, a bearing plate having an upwardly concave spherical bearing, a supplemental annular bearing member surrounding and located below such bearing and having a spherical surface concentric with the main bearing surface, and 90 an annular channel between the bearing surfaces, the bottom of which is below the lowest point in the bearing surfaces, a crushing head having downwardly convex surfaces engaging both bearing surfaces, and 95 an apron extending downwardly below both such spherical surfaces.
- 100 10. In a gyratory crusher, a concave, a crushing head positioned therewithin and means for gyrating it, the under side of 95 said head having a spherical bearing surface, a supporting element for said head, the upper face thereof having a spherical bearing surface adapted to engage and conform to the bearing surface of the head, said 100 supporting element having a second spherical bearing surface concentric with said first bearing surface, said supporting element having a circumferential oil well separating said bearing surfaces. 105
- 110 11. In a gyratory crusher, a concave, a crushing head positioned therewithin and means for gyrating it, the under side of said head having a spherical downwardly convex bearing surface, a supporting element 110 for said head, the upper face thereof having a concave spherical bearing surface adapted to engage and conform to the bearing surface of the head, said supporting element being provided with means, positioned adjacent its outer edge, effective for preventing the escape of oil therefrom, and for preventing the ingress of foreign material between the bearing surfaces. 115
- 120 12. In a gyratory crusher, a concave, a head positioned therewithin and means for gyrating it, the under side of said head having a spherical bearing surface, a supporting element for said head, the upper surface thereof having a spherical bearing surface 120 adapted to engage and conform to the bearing surface of the head, a second spherical bearing surface upon said supporting element, concentric with said first bearing surface 125 and separated therefrom by a circum- 130

- ferential oil well, a shield removably secured to said head and extending outwardly therefrom and having a bearing surface adapted to engage said outer spherical bearing surface upon the supporting element. 5
13. In a gyratory crusher, a concave, a head positioned therewithin and means for gyrating it, the under side of said head having a spherical bearing surface, a supporting element for said head, the upper surface thereof having a spherical bearing surface adapted to engage and conform to the bearing surface of the head, a second spherical bearing surface upon said supporting element, concentric with but lower than said first bearing surface, and separated therefrom by a circumferential oil well, a shield removably secured to said head and extending downwardly therefrom, 10 and having a bearing surface adapted to engage said outer lower spherical bearing surface. 15
14. In a gyratory crusher, a concave, a head positioned therewithin and means for gyrating it, the under side of said head having a spherical bearing surface, a supporting element for said head, the upper surface thereof having a spherical bearing surface adapted to engage and conform to the bearing surface of the head, a second spherical bearing surface upon said supporting element, concentric with said first bearing surface and separated therefrom by a circumferential oil well, an opposed bearing member on said head adapted to engage said second surface, a hollow cone mounted on said head and extending downwardly beyond and lower than said second spherical bearing surface. 20
15. In a gyratory crusher, a concave, a head positioned therewithin and means for gyrating it, the under side of said head having a spherical bearing surface, a supporting element for said head, the upper surface thereof having a spherical bearing surface adapted to engage and conform to the bearing surface of the head, a second spherical bearing surface upon said supporting element, concentric with said first bearing surface and separated therefrom by a circumferential oil well, an opposed bearing member on said head adapted to engage said second surface, and a skirt extending downwardly and outwardly from said head to a plane lower than that of said second spherical bearing surface. 25
16. In a gyratory crusher, a concave, a head positioned therewithin and means for gyrating it, the under side of said head having a spherical bearing surface, a supporting element for said head, the upper surface thereof having a spherical bearing surface adapted to engage and conform to the bearing surface of the head, a second spherical bearing surface upon said supporting ele- 30
- ment, concentric with said first bearing surface and separated therefrom by a circumferential oil well, an opposed bearing member on said head adapted to engage said second surface, and means for shielding the junction between said outer bearing surfaces from the access of the material undergoing crushing. 70
17. In a gyratory crusher, a bearing plate having an upwardly concave spherical bearing, a concentric supplemental bearing member surrounding it and spaced therefrom, having a spherical surface concentric with the main bearing surface, and a crushing head having a plurality of downwardly convex spherical bearing surfaces engaging said concave bearings. 75
18. In a gyratory crusher, a horizontally extending spherical bearing, a crushing head mounted for gyration thereupon, and being shaped with an opposed spherical bearing surface, an oiling duct extending to and discharging at the surface of one of the bearings, the opposite bearing being broken by an annular oiling passage extending thereabout, the surface of the first mentioned bearing being broken by a pocket in communication with said first mentioned oil duct, of such dimensions as to be in communication with said annular oiling passage at all positions of the head during its gyration. 80
19. In a gyratory crusher, a crushing head having a lower spherical bearing surface, a support therefor having an opposed concentric horizontally extending spherical bearing surface, an oil duct extending to and discharging at the surface of the spherical bearing, one of the bearing surfaces being broken by an annular oiling passage extending thereabout, and an annular sump, extending about the periphery of the spherical bearing surface of said support, closed by the crusher head. 90
20. In a gyratory crusher, a crushing head having a lower spherical bearing surface, a support therefor having an opposed concentric horizontally extending spherical bearing surface, an oil duct extending to and discharging at the surface of the spherical bearing, one of the bearing surfaces being broken by an annular oiling passage extending thereabout, an annular sump, closed by the crushing head, extending about the periphery of the spherical bearing surface of said support, a main oil sump, an oil pump, and an oil circuit including said sump, pump, oil duct and annular sump, and means for actuating said pump to pump oil through said first mentioned duct to the surface of the spherical bearing. 110
21. In a gyratory crusher, a crusher shaft and means for gyrating it, a one-piece conic head mounted on said shaft, a spherical bearing surface upon said shaft. 125

surfaced bearing portion on the lower side of said head, an apron extending outwardly and downwardly beyond said spherical bearing portion, and a circumferential flange inwardly projecting therefrom, the lower side of said flange being formed with a spherical bearing surface concentric with

that of said first mentioned spherical bearing portion.

Signed at Los Angeles, county of Los Angeles and State of California, this 21st day of March, 1925.

EDGAR B. SYMONS.
